DUMP CAR DOOR MECHANISM

George B. Dorey, Montreal, Quebec, Canada, assignor to Enterprise Railway Equipment Company, Chicago, Ill., a corporation of Illinois

Application December 8, 1950, Serial No. 199,742

4 Claims. (Cl. 105—300)

1

My invention relates to an improved dump car door operating mechanism employed for raising and lowering the discharge door of a railway dump car, and is especially adapted to meet special conditions which arise in connection with a type of car used for depositing ballast at the sides of the rails and involving a door which when in closed position extends upwardly at an incline and swings downwardly to an inclined opened position.

The objects of the invention among others are the provision of a winding sheave for a flexible connection extending between said sheave and door wherein the sheave is maintained in axial alignment on a shaft by means of guiding walls extraneous to the sheave and together provide for guiding a flexible connection to maintain a straight line path by guiding means disposed independently of the sheave.

My invention further resides in the construction involved in the structural relation between a winding sheave and the lower reinforcing beam of the hopper whereby a flexible connection extends through the lower flange of said beam and in the cooperation between the hopper structure and mechanism parts such as will be pointed out.

For further comprehension of my invention reference may be had to the accompanying drawings showing my improvements embodied in connection with the door of a side discharging ballast car.

In said drawings Figure 1 is an end elevation view of the outer end of a hopper showing my improvements applied thereto.

Figure 2 is a longitudinal side elevational view of a portion of the side of a car showing in side elevation the structure shown in Figure 1 and illustrating one door in relation to the car structure having my invention applied thereto.

Figure 3 is a plan view of the structure illustrated in Figures 1 and 2 with portions thereof broken away to better illustrate my improved sheave structure and guiding walls.

Figure 4 is a vertical transverse sectional view on an enlarged scale taken through the door and related car structure as viewed on a line 4—4 of Figure 2 with the door in closed position.

Figure 5 is a view similar to Figure 4 except that the door is shown in open position.

Figure 6 is a fractional sectional view on an enlarged scale taken on a line 6—6 of Figure 4.

Figure 7 is a detail frontal elevational view of one of the winding sheaves showing the same in detached relation.

Figure 8 is a side elevational view of the sheave shown in Figure 7 as viewed from right to left.

2

Figure 9 is an end elevational view of a beam showing a modified form of structure for the lower flange of the beam.

Figure 10 is a vertical side elevational view of the hopper reinforcing beam shown in Figure 9.

Figure 11 is a sectional plan view of the structure shown in Figure 10 as seen on a line 11—11 of said Figure 9.

Figure 12 is a vertical sectional view on an enlarged scale taken through the beam on a line 12—12 of Figure 10.

Figure 13 is still another modification of the door beam, said figure showing an end view of the beam.

15 Figure 14 is a vertical side elevational view of the beam shown in Figure 13 as viewed from left to right.

In said drawings the car structure as distinguished from the dump door is shown as includ-

20 ing a car side wall in the form of a side plate 10 having a lower reinforcing angle member 11. Sloping downwardly to a lower hopper structure 12 is a sloping floor plate 13 which is reinforced by a substantially channel shaped beam member 14 having a vertically disposed web 15, an upper flange 16 underlying the floor plate 13 and an outwardly directed lower marginal flange 17 which extends beneath the sloping floor plate 13. The hopper extends lengthwise of the car for an appreciable distance and at each end there is provided a transversely extending wall structure indicated generally at 18 which constitute baffle plates for confining the flow of the lading as it flows from the door opening. A hinge rod 19 which is carried by said end wall structures extends lengthwise of said hopper 12 for the entire length thereof and pivotally mounted on said rod is a dumping door 20. The door 20 is provided with a hinge loop structure 21 which encircles the hinge rod 19 and in combination with a facing door 22 forms a continuous hinge and the door 20 is extended towards the beam member 14 to abut the same when the door is in closed position.

45 The door 20 adjacent its hinge and swinging edges is reinforced by longitudinally extending beam members 23 which are preferably of Z shaped construction with one flange 24 underlying the plate of the door 20 and riveted or otherwise secured thereto.

The door is arranged to extend upwardly from its hinge axis to lie in closed position at a slope corresponding substantially to the slope of the upper floor plate 13 and is movable downwardly to an open position to a slope lying at a load shedding angle.

The door is arranged to be raised and lowered by means of winding mechanism which includes a shaft 25 rotatably mounted in bearings 26 at each end of the hopper there being provided on the shafts thimbles 26a to form circular bearings. Non-rotatably mounted on the shaft 25 are winding sheaves 27 and connecting each said sheave and the door 20 is a flexible connection 28 preferably in the form of a coil chain. Each sheave is provided with a pair of lugs 29—29 between which the end link 30 of the chain is received and a rivet 31 extends through said jaws and link.

The opposite end of the connection 28 is connected to the door 20 by means of a threaded eyebolt 32 which extends through the front beam member 23 and an adjacent bracket 33, the latter being secured to the door 20 and welded to the member 23 at 34. The connection 28 extends around the front edge of the door 20 which is notched at 35 and at each side of the notched section the edge of the door is reinforced by gusset plates 36 which are welded to the door plate and front door beam.

Each sheave 27 includes a flat peripheral face 37 extending on a given diameter for its entire width and the edge portions 38 constitute guiding walls with which the vertical walls 39—39 of angle shape members 40 engage to maintain the sheaves 27 in fixed axial relation to the shaft 25. Said angle shaped members 40 are riveted or otherwise secured to the underside of the sloping floor plate 13 and extended to underlie the side wall reinforcing member 11 and the upper flange 16 of the beam member 14. The angle members 40 being disposed at each side of the sheaves 27 form strong reinforcing members for the floor 13 and maintain the latter against buckling due to the impact of dropped lading.

Each connection 28 in its passage from the sheave to the door extends through an aperture 41 formed in the lower flange 17 of the beam 14 and in alignment with the sheave 27, the said flange 17 is flared downwardly as indicated at 42. The extent of flange 17 included in flare 42 includes a portion of the aperture 41 and the edge portion 43 of said aperture lies immediately adjacent the peripheral surface 37 of the sheave 27 and operates to maintain said surface free of clay and mud as may be gathered by the connection and deposited on the face of the sheave 27 during the door raising operation.

In order to seal the openings formed by the notches 35 in the door plate 20 there is secured to the outer face of the beam 14 a sealing plate 44 which includes a lip 45 extending to overlie the notch 35.

The employment of my improved mechanism permits the location of the beam member 14 in close proximity to the sheaves 27 resulting in a wide load containing space between the beam members on the respective sides of the car and making for large load carrying capacity, and most importantly allows the use of a supporting beam of great strength both vertically and laterally.

The rotation of the shaft 25 may be effected by any suitable rotating means (not shown). In the course of the swinging movement of the door from closed to opened positions or vice versa the sheaves 27, as will be observed by reference to Figures 4 and 5, rotate an angular distance less than a complete revolution and the lugs 29 move from a position at the side of the marginal flange 17 to a position above the same and during such

movement each flexible connection 28 is maintained in place over the face 37 of the associated sheave by reason of extending between the guiding walls 39—39 and through the aperture 41.

In the modification shown in Figures 9, 10, 11 and 12 there is shown a structure wherein the sloping floor reinforcing beam 110 is formed with a comparatively narrow reinforcing flange 111 and at each connection the said flange is formed with an open notch 112, and across the interrupted flange there is disposed a reinforcing plate 113. The said plate 113 is apertured at 114 for the accommodation of a flexible connection therethrough and the said apertured section is flared downwardly as indicated at 115 to clear the sheave 27 as heretofore described.

In the construction shown in Figures 13 and 14 this beam is shown as including a vertical web 210, an upper flange 211 and a lower flange structure including a substantially horizontally extending wall 213 having its outer margin 214 flanged downwardly for its entire length. Apertures 215 are formed in the depending flange 214 and horizontal wall 213 for the accommodation of the flexible connections therethrough.

What is claimed as new is:

1. In a load discharging car having a hopper including a stationary upper sloping floor and a beam extending lengthwise beneath the marginal edge of the floor, said beam having an upstanding web and a lower marginal flange extending inwardly beneath the sloping floor; a discharge door pivotally mounted on an axis spaced from the reinforcing beam, said door being swingable to closed position to meet with the beam; a winding shaft rotatably mounted outwardly of the beam; a sheave non-rotatably mounted on said shaft and axially movable thereon; a pair of spaced walls carried by said sloping floor on the underside thereof straddling the sheave to prevent lengthwise movement thereof; said beam having an aperture in its lower flange, said aperture being disposed in alignment with the sheave; those portions of the flange on opposite sides of said sheave being flared downwardly and interconnected by a portion of said flange in close proximity to the surface of said sheave whereby said portion acts as a scraper to keep said surface clean; and a flexible connection between the sheave and door extending through the aperture of the door beam and guided on the sheave by the spaced walls.
2. In a load discharging car having a hopper including a fixed floor structure and a discharge door pivotally mounted on the car structure and swingable to closed position with its swinging edge meeting with the fixed floor structure; a winding shaft rotatably mounted on the car structure beyond the swinging edge of the door; a sheave non-rotatably and axially slidably mounted on the shaft; a flexible connection connected to the sheave and door for raising and lowering the door by rotation of the shaft; and guiding walls on each side of the sheave carried by the car structure and forming a channel within which the flexible connection extends and is maintained in a straight line path over the periphery of the sheave, said walls also preventing axial movement of said sheave along said shaft.

3. In a load discharging car having a hopper including a stationary upper sloping floor and a reinforcing beam extending lengthwise beneath the marginal edge of the floor, said beam having an upstanding web and a lower marginal flange

extending outwardly beneath the sloping floor; a discharge door pivotally mounted on an axis spaced from said beam, said door being swingable to closed position to meet with said beam; a winding shaft rotatably mounted outwardly of said beam; a sheave non-rotatably and axially slidably mounted on said shaft; means cooperating with said sheave to prevent axial movement thereof along said shaft; said beam having an aperture in its lower flange in alignment with said sheave; and a connection between said sheave and door extending through said aperture in said lower flange and guided by the walls thereof to wind on said sheave.

4. In a load discharging car having a hopper including a stationary upper sloping floor for directing lading to a discharge opening, said floor having a floor beam extending lengthwise beneath the marginal edge of said floor, said beam being of substantially channel shape with a vertical web defining a wall section of the hopper and a lower flange extending beneath the sloping floor; a discharge door pivotally mounted on an axis spaced from said beam, said door being swingable to closed position to meet with said lower flange of said beam; a winding shaft ro-

tatably mounted outwardly of said beam and above its lower flange, a sheave non-rotatably and axially slidably mounted on said shaft, means cooperating with said sheave to prevent axial movement thereof along said shaft, a connection from said sheave to said door, said connection extending through said lower flange of said beam, said flange being apertured in alignment with said sheave for the accommodation of the connection therethrough and guiding the same to wind on said sheave and said flange being flared downwardly at each side of said sheave so that the plane of said flange extends through said sheave.
